United States Patent Office

Des. 176,604
Patented Jan. 10, 1956

176,604

AIRPLANE

Wendell B. Fehring, Wichita, Kans., assignor to Boeing
Airplane Company, Wichita, Kans., a corporation of
Delaware

Application May 26, 1955, Serial No. 36,221

Term of patent 14 years

(Cl. D71—1)

FIG. 1

FIG. 2

FIG. 3

FIG. 4

FIG. 5

Fig. 1 is a side elevational view of an airplane embodying my new design;

Fig. 2 is a top plan view of the same;

Fig. 3 is a front elevational view of the same;

Fig. 4 is a perspective view of the same taken from a point above the airplane; and

Fig. 5 is a rear elevational view of the same.

The essential features of my design reside in the portions shown in full lines.

I claim:

The ornamental design for an airplane, as shown and described.
